UNITED STATES PATENT OFFICE.

GEORGE CANNING STRACHAN, OF DETROIT, MICHIGAN.

BATHTUB.

1,348,250.

Specification of Letters Patent. Patented Aug. 3, 1920.

Application filed January 8, 1919. Serial No. 270,115.

To all whom it may concern:

Be it known that I, GEORGE C. STRACHAN, a British subject, residing at Detroit, county of Wayne, State of Michigan, have invented 5 a certain new and useful Improvement in Bathtubs, and declare the following to be a full, clear, and exact description of the same, such as will enable others skilled in the art to which it pertains to make and use the 10 same, reference being had to the accompanying drawings, which form a part of this specification.

My invention relates to an auxiliary detachable bath tub for infants' use, employed 15 in connection with an ordinary stationary tub.

The object of this invention is to provide a relatively small bath tub adjustably supported within the usual stationary bath tub, 20 the construction being such that the small tub may be raised and lowered so that a child may be easily bathed by the nurse in charge.

A further object of the invention is to 25 provide for the delivery of water to the auxiliary tub and its subsequent discharge into the main tub, that the water so delivered may pass off through the sewerage system of the latter.

With the foregoing and other objects in 30 view which will appear as the description proceeds, the invention resides in the combination and arrangement of parts and in the details of construction hereinafter described and claimed, it being understood 35 that changes may be made in the precise embodiment herein disclosed without departing from the spirit of the invention.

In the drawings accompanying this specification:

Figure 1 is a perspective view of an ordinary stationary bath tub with my auxiliary tub supported therein. Fig. 2 is a longitudinal vertical sectional view of the same;— 45 showing a hose pipe connection leading from the faucet of the stationary tub to the auxiliary tub.

Fig. 3 is a cross-sectional view on line 3—3 of Fig. 2.

50 Fig. 4 is an inverted plan view of the auxiliary tub, showing the means for engaging the adjustable supporting arms to the tub.

Referring now to the letters of reference placed upon the drawings:—

A, denotes a stationary tub of usual construction. B, denotes a relatively small tub provided upon its underside with brackets C, adapted to receive adjustable supporting rods D, extending transversely across the bottom wall of the tub. 55

E, designates set screws for securing the bars in the bracket when properly adjusted. F, indicates L-shaped bars, adjustably mounted in a suitable fitting G, secured to the outer end of the rods D. H, denotes a 60 set screw in said fitting for securing the bars F, when adjusted. I, is a rubber cushion on the end of the bars resting upon the edge of the stationary tub.

J, is a drain-off plug in the lower wall of 70 the tub and K indicates a perforated lug for suspending the tub from a nail when not in use.

M, is the usual faucet connection for the stationary tub, and N, is a hose pipe connection between the faucet and the auxiliary tub. 75

Having indicated the several parts of the invention by reference letters, the construction and operation of the same will be 80 readily understood.

Having thus described my invention, what I claim is:—

A device of the character described, comprising a bath tub, brackets secured to the 85 bottom of said tub, a plurality of rods extending transversely through said brackets, means for securing the rods in said brackets when adjusted, fittings secured to the outer end of said rods, vertically adjustable members 90 extending into said fittings for supporting the tub at different altitudes upon the walls of a relatively larger tub, and means for securing said vertically adjustable members in rigid relation to the fittings 95 when adjusted.

In testimony whereof I sign this specification in the presence of two witnesses.

GEORGE CANNING STRACHAN.

Witnesses:

S. G. THOMAS,
JOHN CONSIDINE, Jr.
